VENETIAN BLIND

William Wade, Chicago, and Edwin North, Rockford, Ill., assignors to National Lock Company, Rockford, Ill., a corporation of Delaware

Application January 28, 1937, Serial No. 122,793

11 Claims. (Cl. 156—17)

This invention discloses certain improvements in Venetian blinds, and combination supporting and operating means therefor.

Among the important objects of the invention are the provision of supporting means for the blind assembly in the form of brackets attachable to a window casing, and having a carriage member extended therebetween from which flexible blind supporting and control elements are suspended to maintain the slats in their operative relationship.

A further and important object is the provision of a carriage member having pin and slot supporting engagement with mounting brackets as aforesaid, whereby the carriage may readily be installed or dismounted without the need of tools or special skill.

A further and more specific object is the provision of blind supporting and operating mechanism including bracket members attachable to a window casing and having a carriage pivotally supported between the brackets, such support being effected by means of pin and slot engagement of a pivotable bracket member with one of the axial extremities of the carriage such that the carriage may be slid or positioned at said extremity into and out of supporting engagement with the corresponding bracket, the opposite extremity of the carriage being provided with a pivoted housing member adapted for supporting engagement with the other said bracket and including also part of the blind operating or control mechanism, the said housing being positionable in mounted and supported relation with its corresponding bracket by a form of pin and slot arrangement whereby the entire carriage may be mounted in operating position by simply fitting or sliding the carriage into supported position with the pin and slot members of the brackets.

Other objects of the invention are directed to the provision of a combination supporting and operating means for blinds, which is relatively simple, inexpensive, rugged, and which will take up the least possible amount of space in mounted position on the window casing.

Other novel objects of construction and operation, including certain features of the blind operating mechanism, will appear as the following specification proceeds in view of the annexed drawings, in which:

Fig. 1 is a front elevation of the novel blind mounted in a window casing;

Fig. 2 is an enlarged vertical section showing

the chain rollers on the carriage, and taken along lines 2—2 of Fig. 1;

Fig. 2A is an enlarged vertical sectional detail of a lower chain attaching cleat, and taken along lines 2A—2A of Fig. 1;

Fig. 3 is an enlarged perspective detail of the trunnion pin mounting bracket which is positioned at the upper right-hand corner of Fig. 1;

Fig. 4 is an enlarged perspective detail of the combination roller housing and end carriage support and mounting bracket therefor;

Fig. 5 is a top plan view taken along lines 5—5 of Fig. 1, and showing the roller housing with the top cut away and the supporting bracket in horizontal section;

Fig. 6 is a vertical section through the pivoted roller housing, and taken along lines 6—6 of Fig. 5;

Fig. 7 is an elevation of the combination housing pivot and chain pay-hole, viewed from the interior of the housing in the direction of line 7;

Fig. 8 is a vertical section through the housing, taken along lines 8—8 of Fig. 7, corresponding to a median vertical plane through the pay-hole and to a rear side view of the device of Fig. 5;

Fig. 9 is a vertical section of the trunnion bracket taken along lines 9—9 of Fig. 3;

Fig. 10 is an enlarged vertical section taken along lines 10—10 of Fig. 9;

Fig. 11 is an enlarged vertical detail, partly in section, of the pulley and guide sleeve, and is taken along lines 11—11 of Fig. 10;

Fig. 12 is an enlarged perspective detail of one of the slat clips; while

Fig. 12A is an enlarged perspective fragment of a slat and clip slot therein.

The blind structure which forms part of the present invention is related in a general sense to a blind structure shown in applicant's co-pending case Serial No. 122,794, filed Jan. 28, 1937. The so-called Venetian blind is well known and includes a plurality of slats supported in spaced relation by flexible members such as cloth strips, so that the slats may be tilted or folded together.

The blind of the present invention likewise includes a plurality of spaced slats 16 supported between pairs of chain elements 18 from a top rail or carriage 20, as seen in Fig. 1 for example. The carriage, in turn, is pivotally supported between a pair of mounting brackets 22 and 24 (Figs. 1, 3, and 4) which are fitted and secured into the upper corner portions, respectively, of a window casing 26.

The group of slats includes a bottommost slat 15 which is preferably heavier than the others

so as to facilitate the lowering of the blind, and as seen in Fig. 1 this lower slat 15 is provided with a pair of axially disposed end pins 28, each of which extends into a vertically disposed track member 30 attached to the inner side portions of the window casing. In this manner a uniform vertical movement of the slat assembly is assured.

The supporting elements or chains 18 are arranged in pairs on opposite sides of the slats, both chains 18 and 18' of each pair being movably attached at their lower extremities to a cleat 19 which, in turn, is attached to the edge of the lower slat by means of nails 21 or the like. Each of the cleats 19 is in the form of an elongated channel or U-shaped metal piece having a bottom wall 23 and a pair of oppositely disposed upturned side walls 25 adapted to fit over the edge portions of the slat. The main or bottom wall portion 23 of these cleats is provided with an eye or loop 21, to which the bottom links of the chains 18 and 18' of a pair are attached.

The outermost chain 18 of each pair (see Fig. 2) extends upwardly toward an opening in the bottom of the carriage or top rail 20, and is attached to the latter by means of an elongated pin 32 which extends beyond the margins of the hole on the inner bottom side of the carriage and which is secured in place by a pair of overturned ears 33 struck out from the carriage wall.

Each outer chain 18 of each pair is pivotally attached to each of the intermediate slats by means of clips 34 (Fig. 12), these clips being in the form of elongated resilient metal strips bent back upon themselves and having crimped end portions forming an upper lip 35 and a lower inwardly turned hump 36 which is receivable in slots 17 formed on the underside of each of the intermediate slats adjacent their edge portions (Fig. 12A). A wire ring or loop 37 is fitted around the bight portion of each clip and has its end portions 38 flared outwardly through openings in a chain link. Each of these loops 37 is large enough to permit the passage therethrough of the innermost chains 18' between the clip and the outer chain 18, and in this manner the inner chains 18' are each guided in their upward extension toward and through their respective collared openings 39 in the bottom wall 50 of the carriage 20. The novel clips 34, such as shown in Fig. 12, are fully described and claimed in applicant's co-pending application, Serial No. 122,795, filed Jan. 28, 1937.

After passing through the bottom of the carriage, the uppermost reaches of each of the inner chains 18' pass over horizontally disposed rollers 40 pivoted on the inner bottom walls of the carriage, these chain members thereafter being led from the rollers toward the left-hand end of the carriage, as seen in Fig. 4, into and through a pay-hole 41 formed in the upturned end portion 42 of the carriage, from whence they pass into the roller housing 43 at the left end of the carriage.

In the disposition illustrated in Fig. 4 for example, the innermost chains 18' are four in number, and after passing through the roller housing 43 they terminate in a common connection with a pull-chain clamp 44 by means of which they are joined to a ball type of pull-chain 45.

It will thus be apparent that one chain of each pair is attached by means of a clip to the edge of each slat, and these particular chains are secured at their respective extremities to the bottommost

slat and to the bottom wall of the carriage, and since there are two of these chains on either side of the group of slats, it will follow that if the carriage is tilted about its long axis the chains 18 on one side of the slats will descend while the chains on the opposite side will rise, this motion being transmitted to the edge portions of each slat and causing the same to be tilted about their long axes. Thus the slats are tilted from their normal horizontal position into vertically directed positions so as to open and close the blind in the fashion of a shutter.

Each of the inner chains 18', it will be recalled, is attached at its lower extremity to the bottom-most slat and passes at its uppermost extremity over roller means on the carriage, thence through the roller housing 43 from where it issues to a common juncture with the pull-chain 45, the operation of which will serve to raise the lower-most slat when pulled downwardly so as to move the slat upwardly against the intervening slats and raise the latter toward the carriage.

The rollers 40 turn on shaft pins 46 which extend between the upturned side wall portions 47 of the carriage, and the rollers are desirably provided with hoods 48 in the form of metal strips bent into a double U shape with the shaft pin 46 extending through the vertical wall portions thereof so as to loosely hold the hood in position over the rollers.

At one extremity (the right-hand end as seen in Fig. 3) the carriage 20 is provided with an upstanding end wall 49 in which are a pair of spaced openings 50 positioned to receive a pair of trunnion pins 51 extended in a horizontal direction laterally away from the extremities of a trunnion arm 52, which in turn is pivotally mounted on a stud 53 extended from the bight portion of a U-shaped bracket 54 attached to a vertical wall portion 55 of the mounting bracket 24 (Figs. 3, 9, and 10).

The trunnion arm 52 has an integrally formed segmental gear 56 and a pair of integral stopping ears 57 formed adjacent the respective longitudinal extremities of the arm between the latter and the gear segment 56. The segmental gear 56 is engaged by a driving worm 58 rotatable with a shaft 59 disposed between a pair of brackets 60 extended laterally away from the vertical side wall 55 of the bracket 24 above the trunnion arm 52, the outermost extremities of each of the worm brackets 60 lying in the path of movement of the correspondingly disposed ears 57 on the trunnion arm so as to limit the rotative movement of the same in both directions.

The shaft 59 extends toward the forward edge 61 of the bracket 24 and terminates in the pulley 62, keyed and secured thereto by means of an end screw 63 and having a pulley track formed with a plurality of recesses for the reception of an endless pulley chain 64, the operation of which rotates the worm 58 and causes the trunnion arm 52 to rotate about the stud 53, and as a result causes the carriage 20 to be pivoted about its long axis since the carriage is supported at this end on the trunnion pins 51.

The specially formed chain pulley 62 is provided with a combination hood and sleeve 65 which prevents removal of the chain 64, and also assures positive engagement of the same with the pulley at all times. This latter mechanism forms part of applicant's co-pending application, Serial No. 122,795, filed Jan. 28, 1937, which may be referred to for a more detailed description of this novel device.

At its opposite (left-hand) extremity, as seen in Fig. 4, the carriage 20 is provided, as before mentioned, with an upstanding end wall 42 through which extends the chain pay-hole 41. This pay-hole is formed by a stud sleeve 70 flared or peened over at its carriage extremity, securing it to the end wall, and provided with an enlarged collar portion 71 at its inner extremity and overlying the corresponding side wall of the roller housing 43 so as to attach the latter to the carriage and provide an axis about which the housing may be tilted. The housing 43 comprises a box-like member including a bottom wall 72 and having an open end and top normally closed by a curved cover plate 73. A roller 74 is pivotally mounted, as at 95, between extended opposite side wall portions of the housing, the several chains 18' being adapted to pass over this roller between the same and the vertical portion of the plate 73.

20 Inferiorly of the housing, a vertical roller 75 revolves about a stud 76 (Figs. 5, 6, and 8) attached to and extended from the bottom wall 72, the upper end of the stud being threaded internally to receive a screw 77 which serves to secure 25 the cover plate 73 and the roller 75 in proper position.

The disposition of the roller 75 relative to the center line or axis of the pay-hole 41 is such that the periphery of roller 75 is substantially tangent 30 with the center line or axis of the pay-hole, so that the chains 18' issuing through the pay-hole from the carriage 20 will at all times be disposed for free movement through the pay-hole and around the rollers 75 and 74, regardless of the 35 position of the housing 43 with respect to its pivot about the stud 71.

The housing 43 is designed and balanced so as to fall normally in a downward direction about its 40 pivotal axis, as seen in Fig. 4, the latter illustration, however, showing the housing in raised position ready to be secured in place in its bracket, the lower position of the housing serving to facilitate the sliding of the carriage into mounting 45 position in the relatively close space provided for the assembly at the top of the window casing, the housing being tilted in the position shown in Fig. 4 when the carriage is otherwise properly in place to secure the assembly finally in mounted 50 position by the means now to be described.

50 The bottom wall 72 of the housing 43 is provided with a co-extensive lug 78 and a depending ear or lug 79, each of which is respectively adapted to fit into receiving slots 78' and 79' formed in a horizontally disposed plate 80 extended laterally away from the vertical side wall portion 22' of the left mounting bracket 22, it being observed that the slot 79' is formed in the main horizontal body portion of the member 80, while the slot 78' is formed adjacent the bend of an upturned portion 78'' of the member 80.

It will thus be apparent that assuming the right-hand end of the carriage 20 to be fitted upon the trunnion studs 51, the opposite or left-hand end of the carriage may be secured in 65 mounted position by simply tilting the housing 43 into the position shown in Fig. 4, so as to cause the lug 78 and the bottom thereof to slide into its receiving slot 78' in bracket 22 and thereafter pivoting the housing downwardly so as to position the depending lug 79 in its receiving slot 79', this latter movement being very quickly and easily effected by virtue of the peculiar disposition 70 of the lugs and slots, and also by virtue of the tendency of the housing normally to fall into lowered position. It will also be observed that,

as shown in Fig. 4, the slots 78' and 79' are enlarged so as to permit a determined amount of play or movement of the carriage in an axial direction, the trunnion pins 51 being dimensioned to permit a similar degree of play without passing 5 out of the receiving apertures 50 in the corresponding end wall of the carriage. In this manner variations in the width of the window casing are provided for, this feature of the invention being covered in applicant's co-pending case, 10 Serial No. 122,794, filed Jan. 28, 1937.

As seen in Figs. 2 and 3, each of the mounting brackets 22 and 24 is provided with three adjacent wall portions adapted to confront the correspondingly disposed surfaces of the corner of the window casing, the brackets being attached to the latter by means of screws 67 or the like extended through mounting holes 69 in the several side wall portions of the brackets.

Each of the brackets 22 and 24 is provided 20 with ears 68 struck up from their respective vertical wall portions 22' and 55, these ears being adapted to be engaged by depending resilient lip or flange portions 81 formed along the longitudinal edges of a suitably figured or decorated 25 valance plate 82 (Figs. 1 and 2), the resiliency of these flange portions being adapted to permit snapping the valance plate into position on and between the two brackets 22 and 24, thus shielding the entire bracket and carriage structure from 30 view and completing the ornamental and artistic design of the blind structure.

The blind may be made to raise and lower with some of the slats in nested relation while others remain in spaced relation, so that the blind may 35 hang at a predetermined level partially raised in the manner of the usual roller shade. This is accomplished by applying pickup loops 90 (Figs. 1 and 12) to the inner or lifting chains 18' just below the clips corresponding to the approximate 40 level to which the bottommost slat is intended to rise when the blind is raised. These pickup loops or rings 90 may desirably be in the form of metal spirals having more or less resiliency whereby they may be readily looped onto one 45 or another of the chain links, the particular construction and operation of these loops or rings being fully described and claimed in applicant's co-pending case, Serial No. 122,796, filed Jan. 28, 1937.

50 The advantages of the novel blind structure are thought to be self-evident from the foregoing description in view of the drawings, and it is particularly emphasized that we have provided a simplified blind structure which is extremely 55 rugged and at the same time simple and inexpensive to manufacture and install. The mounting brackets are readily secured to the upper corner portions of a window casing and the tracks 30 which guide the blind are likewise readily applied to the inner sides of the casing, so that the blind may thereafter be mounted in position by simply sliding the right-hand end of the carriage onto the trunnion pins 51 and thereafter settling the left-hand end of the carriage onto the 65 bracket plate 80 and simultaneously sliding the lug 78 into the slot 78', the housing 43 thereafter falling into place automatically and positioning its lug 79 in the slot 79', thus firmly securing the 70 entire carriage structure into operative position.

75 It will be apparent that various modifications may be made in the foregoing particularly described embodiment without departing from the spirit of the invention, and we desire to avail ourselves of all such modifications and any and all 75

variations and applications of the features disclosed herein and coming within the scope of the appended claims.

Having thus described our invention, what we claim as new and desire to protect by Letters Patent is:

1. Blind supporting means including a main support, a plurality of blind slats suspended by flexible elements from said main support; and a pair of end supports attachable to a window casing, and one of the same having mounting pin means extended therefrom and receivable in an opening in an end of said main support, said main support having an end opposite to said last mentioned end and provided with a pivoted member having pin and slot engagement with the remaining end support of said pair whereby said main support may be readily slipped into and out of mounted position relative to said end supports.
2. Blind supporting means including an elongated main support, a pair of mounting brackets attachable to a window casing adjacent the axial extremities of said main support, one of said brackets having extended pin means receivable in the axial end portion of said main support and the latter having a member pivoted for movement about the long axis of said main support and having pin and slot engagement with the other said bracket of said pair, said main support having flexible means suspended therefrom for supporting engagement with blind members.
3. Supporting means for a Venetian blind, said means including an elongated carriage member and bracket members attachable to a window casing at the axial extremities of said carriage, one of said brackets having pin means extended from a movable arm on said bracket and receivable in the corresponding axial end portion of said carriage, the opposite end of said carriage having a member attached thereto for pivotal movement in a direction about the long axis of said carriage, said member having pin and slot engagement with the correspondingly positioned one of said bracket members, said carriage having flexible elements suspended therefrom and slats engaged by said elements, and being pivotable about its long axis relative to said bracket members to tilt said slats.
4. Blind supporting and operating means including a pair of bracket members attachable to a window casing or the like, an elongated carriage member supported between said brackets for pivotal movement about its long axis and being supportably engaged with said brackets by pin and slot means, flexible means depending from said carriage and supporting a plurality of slats in spaced relation therebelow, manually operable means for pivoting said carriage to tilt said slats, roller means on said carriage, a plurality of elongated flexible elements each attached at one of their respective extremities to a lower one of said slats and passing over said roller means whereby the said elements may be moved over said roller means to raise and lower said slats, together with manually engageable means connected with said last-mentioned flexible elements for raising and lowering the slats as aforesaid.
5. A Venetian blind including a pair of bracket members attachable to a window casing, an elongated carriage member extended between said bracket members, one of the latter having a pivoted arm with pin means extended therefrom into the corresponding axial end portion of said

carriage, manually operable means supported by said last mentioned bracket member for pivoting said arm, a housing member attached to the opposite end portion of said carriage for movement about the long axis of the latter, roller means in said housing, roller means on said carriage, said housing having pin and slot engagement with the correspondingly positioned one of said bracket members, a plurality of elongated flexible elements suspended from said carriage, a plurality of slat members attached to said flexible elements and adapted to be tilted by pivotal movement of said carriage, and other flexible elements attached to a lower one of said slats and passing over said roller means in said carriage through said housing and over the roller means therein in such manner that the said last-mentioned flexible elements may be moved over said roller means to raise and lower said slats.

6. A Venetian blind including a pair of bracket members attachable to a window casing, an elongated carriage extended between said brackets, one of the latter having a pivoted arm and spaced pin members disposed radially of the axis of pivot of said arm and receivable in openings in a corresponding axial end of said carriage, manually operable mechanism on said bracket member for pivoting said arm, said carriage having at its opposite axial extremity a housing member pivotally attached thereto for movement about the axis of the carriage, said housing having an opening disposed co-axially with the axis of pivot of the carriage, roller means in said housing and disposed tangentially of the main axis of said opening, roller means on said carriage, a plurality of elongated flexible elements extended into said housing over the said roller means therein through the said opening thereof over the said roller means on said carriage and downwardly away from the latter for connection with the slat member, other elongated flexible elements suspended from said carriage and attached to said last-mentioned slat member, a plurality of slats disposed between said carriage and said first-mentioned slat and pivotally attached to said last-mentioned flexible elements whereby said several slats may be tilted when said carriage is pivoted as aforesaid, and said slats may be raised and lowered by a corresponding movement of said first-mentioned flexible elements over said roller means, said housing having pin and slot engagement with its corresponding said bracket member.

7. A Venetian blind including a first bracket member, a yoke-shaped trunnion arm pivotable on said bracket, a second bracket member spaced away from said first bracket member, an elongated carriage extended between said bracket members and supportably engaged at one axial extremity by said trunnion arm, said carriage having a pivoted member at its opposite axial extremity, an opening disposed co-axially with said carriage and communicating between the same and said pivotally mounted member, roller means supported by said last-mentioned member tangentially to said opening, said pivotally mounted member having pin-and-slot and bearing engagement with said second bracket member and having flexible blind operating means extended over said roller means through said opening for movable suspension from said carriage and operative engagement with blind means disposed therebelow, manually operable

mechanism for pivoting said trunnion arm, and flexible means extended from said carriage and pivotally attached to blind members for tilting the same when said carriage is pivoted.

- 5 8. A Venetian blind including a pair of bracket members having rectangularly disposed wall portions adapted to fit for attachment in opposite upper corner portions of a window casing, one of said brackets having a first pivoted member with 10 stud means thereon receivable in the axial end wall of a carriage member, manually operable mechanism for pivoting said first pivotable member, an elongated carriage supportably engaged at one axial extremity with the stud means in 15 the manner aforesaid, and having a housing member pivotally attached at its opposite axial extremity and movable in a direction about the axis of the carriage, said housing having an opening communicating with said carriage and substantially co-axial with the axis of pivot of 20 the same and of the said housing, and the latter having roller means disposed tangentially to said axis of pivot, the correspondingly positioned one of said bracket members having a horizontally disposed plate member against which said housing member is adapted to rest, said housing being held in position thereon by pin and slot engagement therewith, a plurality of slat members suspended by flexible elements from said carriage and adapted to be tilted by pivot of the latter as aforesaid, together with flexible means attached to the lowermost one of said slats and extended into said carriage through the aforesaid opening and through the said housing 25 over the roller means therein, the said last-mentioned flexible means being operable to raise and lower said blind and the slats thereof.

- 30 9. Blind supporting and operating means including bracket members attachable to a support, 40 an elongated carriage member mounted between and on said bracket members for pivotal movement about its long axis, said carriage having a pivoted member at one extremity and being pivotable in a direction about said long axis of the 45 carriage, said pivoted member being adapted to rest upon a horizontal portion of the correspondingly positioned said bracket member and having means engageable with said bracket and effective to prevent sliding disengagement of said pivoted member therefrom, a plurality of spaced slats suspended from said carriage, together with 50 manually engageable flexible means extending from said pivotally mounted member and through said carriage for engagement with one of said 55 slats and manually movable to raise and lower the same.

10. A Venetian blind including a pair of brackets for attachment to a support, an elongated carriage plate having oppositely disposed vertical end walls, one of which is provided with a pair 60 of openings spaced equally from the long axis of

said carriage, a pivoted arm on the corresponding end bracket and having spaced stud means receivable in said openings, the opposite end of said carriage having an opening in its end wall disposed co-axially with said pivoted arm, a roller 5 housing secured to said carriage for pivotal movement about the long axis thereof concentrically with said last opening, said housing having a roller disposed vertically therein and tangentially of the central axis of said last opening, said 10 housing further having a horizontal roller with its axis substantially parallel to that of said last opening, said housing having a bottom portion adapted to rest on a horizontally extending surface of the adjacent one of said brackets and 15 having pin and slot engagement with the same effect to prevent horizontal disengaging movement of the housing from the bracket, blind means suspended by flexible means from said carriage, manually operable means for pivoting 20 said pivoted arm to pivot said carriage and the said blind means, together with flexible means passing over the said roller means in said housing and through said co-axial opening over and through said carriage for operative engagement 25 with said blind means, and operable to move said blind means in a vertical sense.

11. In a Venetian blind, including a plurality of slats suspended by flexible elements in normally spaced relation from a window support or 30 the like, supporting mechanism comprising an elongated carriage from which said flexible elements and slats are suspended, together with mounting means for said carriage including a pair of brackets attachable to a window casing 35 and one of said brackets having a pivoted member having pin and slot engagement with an end of said carriage and movable to pivot the latter about its long axis, manually operable means on said bracket to pivot said arm, a second bracket 40 of said pair having a horizontally extended portion at the opposite end of said carriage and the latter having a housing member with a bottom wall adapted to rest on said horizontal portion of the bracket and having pin and slot en- 45 gagement therewith to prevent horizontal sliding disengagement from said bracket, said housing being pivotally attached to said carriage by a stud sleeve disposed co-axially with the axis of pivot of the carriage, the housing being piv- 50 otal in a direction about said axis and having a vertical roller tangential to the center of said sleeve stud, and a horizontal roller rotatable about an axis substantially parallel to that of the carriage, together with flexible means pass- 55 ing over said rollers through said sleeve stud and said carriage for depending operative engagement with one of said slats to move the same in a vertical sense responsive to manual operation.

WILLIAM WADE. 60
EDWIN NORTH.
